CLAIM

The ornamental design for a "curved front panel for infrastructure equipment," as shown and described.

DESCRIPTION

FIG. 1 is a top plan view of a "curved front panel for infrastructure equipment" showing our new design;

FIG. 2 is a bottom plan view thereof;

FIG. 3 is a front elevational view thereof; and

FIG. 4 is a left side elevational view thereof; and,

FIG. 5 is a top, right and front isometric view thereof.

The phantom lines in FIGS. 3, 4 and 5 are provided for reference only and form no part of the claimed design.
